UNITED STATES PATENT OFFICE.

KARL A. SMEBY AND GAYLORD W. AKIN, OF DENVER, COLORADO.

LICENSE-NUMBER CARRIER.

1,400,630.

Specification of Letters Patent. Patented Dec. 20, 1921.

Application filed September 29, 1919. Serial No. 327,130.

To all whom it may concern:

Be it known that we, KARL A. SMEBY and GAYLORD W. AKIN, citizens of the United States, residing at Denver, in the county of 5 Denver, State of Colorado, have invented certain new and useful Improvements in License-Number Carriers; and we do hereby declare the following to be a full, clear, and exact description of the invention, such as 10 will enable others skilled in the art to which it appertains to make and use the same.

This invention relates to attachments for automobiles and particularly to license number holders therefor.

15 One object of the present invention is to provide a novel and improved form of devices of this character which combine the rear red tail light and the illuminated license number.

20 Another object is to provide a novel and improved device of this character wherein the license number plate and tail light plate may be easily and quickly removed or replaced, so that the number can be changed 25 in accordance with the State in which the automobile is traveling.

Other objects and advantages will be apparent from the following description when taken in connection with the accompanying 30 drawing.

In the drawing:

Figure 1 is an elevation of the license number holder showing the face of the box thereof.

35 Fig. 2 is a vertical central sectional view taken on the line 2—2 of Fig. 1.

Fig. 3 is a horizontal longitudinal sectional view taken centrally on the line 3—3 of Fig. 1.

40 Referring particularly to the accompanying drawing, 10 represents a rectangular metal box which is secured to the rear of an automobile in the desired position, and by any suitable or well known means, so as 45 to be readily seen by other vehicle drivers and pedestrians. The front edge portions of the upper and lower longer sides of the box are bent to form the longitudinal channels 11, and in these channels is arranged to slide 50 the front cover or skeleton plate 12. This plate has the two longitudinally extending openings 13 and 14, and the right end of the plate is bent to the rear to form the flange 15, which engages against one of the end 55 walls of the box. Centrally in this flange 15 there is formed a slotted tab 16 which re-

ceives the staple 17, carried by the said end wall of the box, a padlock or other suitable locking device being engaged through said staple so as to hold the plate against longitudinal movement. Secured to the inner face of the plate 12, and above and below the upper opening 13, are the longitudinally extending angle strips 18, between which is slidably disposed the legend or sign plate 19. This plate 19 is formed of sheet metal in which are cut the abbreviation of the State and the year number, while in one end thereof is cut a circular opening 20. The last two digits 21 of the year number are 60 removable, as shown at 21', thus permitting the owner of the automobile to change the year number. The plate 19 is disposed with its longer edges within the angles of the strips 18 whereby accidental displacement 65 is avoided, it being necessary to first unlock the cover plate and slide the same from the box before the plate 19 can be removed. While we have shown the sign plate as being formed from metal and having the legend 70 cut out in the manner of a stencil, we wish it understood that this plate may be formed of glass with the same opaque except the letter and number openings for the legend. Above and below the lower opening 14 are secured 75 strips similar to the strips 18, and between these strips is a second elongated sign plate 19' having the license number legend 80 thereon.

Within the box, and carried by the end 85 walls thereof, are the electric lamps 22 and 23 to cast light through the stencil openings. Above the lamp 22 is a second lamp 24 which is disposed directly behind the signal light opening 20, a piece of red glass 90 being disposed within said opening.

It will be noted that the outer edge portion of the end wall at the left or opposite to the staple carrying end, extends to a point flush with and is channeled at 11 like the 100 outer edges of the longer sides of the box, whereby when the cover plate, with its legend plates in proper position thereon, is slipped on the front of the box, the inner ends of the said legend plates, or the ends 105 remote from the tab 16, will abut against said extended portion of the end wall and prevent further movement of the cover plate in that direction, while at the same time preventing the removal of the said plates from 110 the cover plate. The said end wall thus prevents removal of the plates at one end while

the flange 15 prevents removal at the other end.

What is claimed is:

A license number carrier comprising a box 5 having its front open and the marginal edge portions thereof formed with channels, one end of the box being open, and a cover plate having its longer side edges and one end edge formed with flanges engaging in the channels, said cover including upper and lower and intermediate parallel longitudinally extending strips, a vertical strip connecting the longitudinal strips at one end, the upper and lower strips each having a longitudinal 10 channel in its inner longitudinal face, the intermediate strip having its upper and

lower faces longitudinally channelled, the said vertical end strip being extended rearwardly to form a cover for the open end of the box, and removable stencil plates engaged in the channels of the strips and being removable with the cover from the box, and removable from the channels of the strips of the cover. 20

In testimony whereof, we affix our signatures, in the presence of two witnesses. 25
